UNITED STATES PATENT OFFICE.

ANTONIO C. PESSANO, OF PHILADELPHIA, PENNSYLVANIA, ASSIGNOR TO
THE GEORGE V. CRESSON COMPANY, OF SAME PLACE.

DESIGN FOR A JOURNAL-BOX.

SPECIFICATION forming part of Design No. 32,587, dated April 24, 1900.

Application filed March 19, 1900. Serial No. 9,332. Term of patent 14 years.

To all whom it may concern:

Be it known that I, ANTONIO C. PESSANO, of the city and county of Philadelphia and State of Pennsylvania, have invented a new and original Design for Journal-Boxes, of which the following is a specification.

My new and original design for journal-boxes is shown in the accompanying drawings, in which—

10 Figure 1 is a plan view of a journal-box embodying the design. Fig. 2 is a side elevation of the same, and Fig. 3 is an end view.

The journal-box consists of a hollow box having a longitudinal cylindrical opening E, 15 extending from end to end.

The box is of an approximately-circular outline in cross-section and tapers toward the ends.

A is the lower portion of the box, and B is 20 the upper part thereof, the latter being of somewhat-smaller diameter and having a longitudinal flange b at each side, along the upper edge of the lower half A. The upper por-

tion B has two transverse ridges C C upon its upper surface, each of which is provided at 25 the middle with a boss c, and in the center of the top of the part B, between the ridges C C, is a recessed boss d. The lower portion A has at the middle of the upper edge, on each side, a lug or projection a.

30 The essential features of the design consist of the hollow box of approximately-circular cross-section, tapering slightly toward the ends and having its upper portion B formed with transverse ridges C C.

35 What I claim as new, and desire to secure by Letters Patent, is as follows:

The design for a journal-box substantially as described and as shown in the accompanying drawings.

40 In testimony of which invention I have hereunto set my hand.

ANTONIO C. PESSANO.
